Athens, Tex.

Application February 26, 1943, Serial No. 477,282

5 Claims. (Cl. 299—110)

This invention relates to a means for extinguishing fires which may have originated in the walls, roof, attic, closets or closed rooms of a building, and it consists in the constructions, arrangements and combinations herein described and claimed.

It is the cardinal object of the invention to provide a means which will permit the discharge of an extinguishing fluid into a closed structure from the interior thereof without liability of permitting air to enter the structure, thus permitting a more ready control of a fire.

More specifically, it is an object of the invention to provide a discharge nozzle which may be actuated so as to penetrate a wall or the like for discharge of the extinguishing fluid at a point adjacent the wall or at a point substantially removed therefrom, the discharge of the fluid at such points being simultaneous or independent as required.

It is also an object of the invention to provide a novel connecting means between the nozzle proper and a discharge hose or the like.

Additional objects, advantages and features of invention will be apparent from the following description and accompanying drawings, wherein

Figure 1 is a side elevation of the nozzle illustrating the device in use,

Figure 2 is an enlarged vertical section thereof,

Figure 3 is a similar view partly in elevation, on the line 3—3 of Figure 2.

Figure 4 is a fragmentary vertical section illustrating the position of the parts for lateral discharge of fluid,

Figure 5 is a cross section on the line 5—5 of Figure 1 illustrating the locked position of a coupling device,

Figure 6 is a similar view illustrating the unlocked position of the coupling device,

Figure 7 is a cross section on the line 7—7 of Figure 2,

Figure 8 is a cross section on the line 8—8 of Figure 2,

Figure 9 is a cross section on the line 9—9 of Figure 4,

Figure 10 is a cross section on the line 10—10 of Figure 2,

Figure 11 is an enlarged vertical section, partly in section, illustrating the valve actuating means,

Figure 12 is a cross section on the line 12—12 of Figure 11,

Figure 13 is a section through the eccentric employed in the device,

Figure 14 is an elevation, partly in section, of the operating rod of the actuating means,

Figure 15 is a cross section on the line 15—15 of Figure 11,

Figure 16 is a vertical section on the line 16—16 of Figure 11,

Figure 17 is a perspective view of the eccentric.

There is illustrated a discharge nozzle generally indicated by the reference character 10 which consists of a fluid inlet 11 and discharge bit or drill 12 interconnected by suitable fittings, as will be described.

A four-way T-fitting 13 is employed, the lateral extensions 14 of which receive tubular members 15 which function as handles for actuating the drill or bit 12, as will be explained in greater detail hereinafter. The vertically disposed extensions 16 and 17 of the fitting have secured respectively therein, a conduit 18 and a coupling fitting 19. The conduit 18 is threaded exteriorly at its lower end and receives a threaded sleeve 20 thereon, the sleeve 20 functioning to mount the drill or bit 12. In the fully engaged position of the drill 12, the latter will abut the lower end of the conduit 18 as shown in Figures 2, 3 and 4. At a point above the lower end of the conduit 18 an arcuate slot 21 is formed for a purpose to be explained.

30 A sleeve 22 is rotatably mounted upon the conduit 18 of a length to extend between a shoulder 23 of the extension 16 and the upper end of the sleeve 20. Suitable gaskets 24 are interposed between the abutting surfaces as shown, and at a 35 point aligned with the slot 21 a similar slot 25 is formed in the sleeve. It will be obvious that the sleeve 22 may be rotated with respect to the conduit 18 and thereby increase or decrease the discharge opening of the slot 21.

40 The drill or bit 12 is of conical formation, the shank 26 of which is exteriorly threaded for snug engagement in the sleeve 20. A plurality of bores 27 extend through the shank and open upon the conical face of the bit and as shown occupy a 45 position in the longitudinal axis of the bit. Additional bores 27' are formed in the body of the shank which are positioned outwardly of the bores 27 and open upon an annular groove 28 formed at the base of the drill head.

50 Reciprocable within the conduit there is a control valve 29 in the present instance consisting of an elongated body 30 through which a bore 31 is formed for passage of fluid to the bit as will be described. The body portion 30 will include suitable packing means 32 effecting a snug

fit within the conduit 18, and as shown includes an inturned flange 32', of a width extending slightly beyond the bore 31, defining a reduced port 32a. Screw threaded fastenings secure the packing to the body 30, as shown, in Figures 2 and 4. The upper end of the bore 31 is threaded and receives therein an operating member 33. The operating member 33 is in the form of a tube slotted longitudinally as at 34 for passage of fluid through the valve 29. The upper end of the member 33 is provided with a pair of spaced ears 35 between which a pull lever 36 is pivotally mounted. The upper end of the lever 36 is pivotally mounted upon an eccentric 37 associated with an operating rod, the latter being suitably mounted in the fitting 13, and disposed exteriorly thereof for ready manipulation of the valve 29, as will now be described.

Attention is invited particularly to Figures 11 to 17 for an understanding of the operating means for the valve 29, wherein it will be seen that one of the handle members 15 house the essential parts of such means. The handle 15 is threadedly engaged in one of the lateral extensions 14, the outer end of which is of reduced diameter, as indicated at 15', and rotatably mounted thereon is a sleeve 115. The sleeve 115 includes an end wall 116 in which a square opening 117 is formed which receives a square tenon of a rod 118. The tenon has a threaded axial aperture 119 for reception of a machine screw 120 which secures the sleeve 115 to the rod. The opposite end of the rod 118 is also formed with a square tenon 121 and threaded bore 122 for mounting of the eccentric 37. The eccentric 37 is formed from a rectangular block of metal, one end of which is formed with a recess 123 complementary to the tenon 121 of the rod. An aperture 124 is formed in the block adapted to align with the aperture 122 of the rod. A machine screw 125 extended through the aperture 124 and engaged in the threaded bore 122 secures the eccentric 37 to the rod 118. The opposite end of the eccentric 37 is formed with a threaded aperture 126 and receives a pintle 137, the outer end of which is enlarged as at 138 and provided with a head 139. The enlarged portion of the pintle forms a bearing for the pull lever 36 as clearly shown in Figure 11.

The rod 118 is supported at its inner end by a combined bearing and gland 140, which in the present instance comprises a cylindrical body member 141 frictionally fit or otherwise secured in the handle member 15. The member 141 has an axial bore through which the rod 118 is extended, and an annular recess interiorly threaded as at 142. The rod 118 has an integral annular enlargement 143 adapted to abut a compression washer 144 interposed therebetween and the base of the gland 140. A gland nut 145 complementary to the threads 142 of the gland is employed to effect a liquid-tight seal, yet permit rotation of the rod 118, by turning movements exerted upon the sleeve 115.

The drill 12 is provided with flutes 12' forming cutting edges, the latter being slightly twisted as indicated at 12'' to effect ready penetration of a roof, wall or the like.

The coupling 19 is formed with a seat 39 adapted to rotatably receive a fitting 40. The fitting 40 is held to the seat 39 by means of a packing nut 41 threadedly engaged in the upper end of the fitting 19. It should be understood that the connection described will permit rotary movements of the discharge nozzle proper.

An elbow fitting 42 is illustrated as connected to the fitting 40 which in turn mounts a coupling device 43 for establishing connection with a fluid nozzle 44.

For an understanding of the construction of the coupling device, attention is particularly invited to Figures 2, 5 and 6. A nipple 45 is employed, cylindrical in shape, one end of which is threaded for engagement with the elbow fitting 42. Rotatably mounted upon the nipple there is a body member 46 of substantial thickness, and within the body member, at diametrically opposite sides there are formed arcuate, tapering passageways 47, the passageways tapering in opposite directions. The nipple 45 is provided with diametrically opposite openings 48 in which respective pins 49 are slidably mounted. The pins 49 have a head 50 and between the heads and a seat formed around the openings 48 respective springs 51 are interposed tending to draw the pins from the openings. The heads of the pins traverse the slots under rotation of the body member 46 and in clockwise rotation of the body member the reduced portion of the slots 47 will contact the heads, forcing the pins inwardly through the openings 48, downwardly behind a flange 52 of the nozzle 44 drawing the flange into snug engagement with a gasket 53 of the nipple 45. The device will thus be effectively coupled to the hose nozzle 44. Counter-clockwise rotation of the body member 46 will bring the greater depth of the slots into operative position with the heads of the pins, allowing the springs 51 to function and withdraw the pins from engagement with the flange 52, and thus allow the nozzle 44 to be disconnected from the device. A closure plate 43' is employed to house the pins and springs and prevent ingress of foreign matter which might affect proper operation of the coupling device.

The operation of the device will be readily understood from the following description. The nozzle 10 being operatively connected with a fire-hose nozzle 44 and it is desired to discharge a fire extinguishing fluid below the roof surface of a building, the drill or bit 12 is positioned at a desired point of the roof and by applying pressure and a rotary movement of the bit, which may be readily accomplished through the handles 15, the edges 12' will effect a cutting action, forming an opening in the roof admitting the nozzle therbelow. It will be understood that the bit 12 forms an opening only sufficient to admit the nozzle therethrough, with slight allowance for easy withdrawal, so that only very little air is admitted within the burning structure. The fluid is now admitted, the valve 29 being in the position shown in Figure 2, the fluid will pass downwardly through the conduit 18, through the slots 34 and bore 31 of the valve and thence through ports 27 and 27'. The ports 27 will provide a direct forward discharge of fluid while the ports 27' assisted by the annular groove 28 will discharge the fluid in an annular lateral direction. Should it be found necessary to discharge the fluid at a point laterally directly beneath the underside of the roof, the sleeve 115 is rotated so as to move the valve 29 to close the ports 27 and 27'. In this position of the valve 29 the slots 21 and 25 are uncovered and permit discharge of the fluid. The sleeve 22 may be rotated to vary the opening of the slot 25 and the position of the slot may be indicated at 54 by suitable markings upon the T-fitting 13.

It is possible to move the valve 29 to an intermediate position so that fluid may be discharged simultaneously through the ports 27—27' and the slots 21 and 25.

While we have shown and specifically described our construction, this is by way of illustration only, and we consider as our own all such modifications in construction as fairly fall within the scope of the appended claims.

We claim:

1. A nozzle for use in extinguishing a fire from the exterior of a building structure comprising a conduit, a hollow fitting secured to one end thereof and a cutting bit fixed to the other end thereof, said fitting being swivelly connected to a source of fluid supply, said cutting bit having a plurality of ports formed therethrough for discharge of fluid from the conduit, the conduit having a slot inwardly of the cutting bit, a valve within the conduit complementary to the ports and the slot for control of fluid therethrough, and control means on said conduit and operatively connected to said valve for operating the same.
2. A nozzle for use in extinguishing a fire from the exterior of a building structure comprising a cylindrical conduit, a hollow fitting fixed to one end of the conduit, a cutting bit secured to the other end thereof, said fitting being swivelly connected to a source of fluid supply, said cutting bit having a plurality of ports extending longitudinally therethrough forming communication with the conduit, the conduit having a slot positioned inwardly of the bit, a sleeve rotatable on the conduit and having a slot aligned with the first-named slot, and a valve in the conduit selectively movable to control passage of fluid through the ports and the slots.
3. A nozzle for use in extinguishing a fire from the exterior of a building structure comprising a cylindrical conduit, a hollow fitting fixed to one end of the conduit, a cutting bit secured to the other end thereof, said fitting being swivelly con-

nected to a source of fluid supply, said cutting bit having a plurality of ports extending longitudinally therethrough forming communication with the conduit, the conduit having a slot positioned inwardly of the bit, a sleeve rotatable on the conduit and having a slot aligned with the first named slot, a cylindrical ported valve reciprocable in said conduit and movable to control passage of fluid through said slots and said ports, and means exteriorly of the conduit for reciprocating the valve.

4. A nozzle for use in extinguishing a fire from the exterior of a building structure comprising a cylindrical conduit, a hollow fitting fixed to one end of the conduit, a cone-shaped cutting bit secured to the other end thereof, said fitting being swivelly connected to a source of fluid supply and having hand grips whereby to rotate the conduit and associated bit, said bit having a plurality of ports extending longitudinally therethrough forming communication with the conduit, certain of the ports opening upon a groove formed adjacent the base of the bit for lateral discharge of fluid, the conduit having a slot positioned inwardly of the bit, a sleeve rotatable on the conduit and having a slot aligned with the first named slot, a cylindrical ported valve reciprocable in said conduit and movable to control passage of fluid through said slots and said ports and means exteriorly of the conduit for reciprocating the valve.

5. The structure of claim 4 in which the means for reciprocating the valve consists of a shaft rotatably mounted in one of the hand grips, an eccentric on the inner end of the shaft within the hollow fitting, a link member pivotally connected between the eccentric and the valve and a sleeve rotatably mounted on the hand grip and connected with the shaft.
